CLAIM

The ornamental design for a cover for electronic device, as shown and described.

DESCRIPTION

FIG. 1 is a perspective view of front, bottom and right side of a cover for electronic device showing my new design; FIG. 2 is a perspective view of front, bottom and left side thereof;

FIG. 3 is a perspective view of rear, top and left side thereof; FIG. 4 is a perspective view of rear, bottom and left side thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof; and,

FIG. 11 is a perspective view thereof, showing the claimed design in condition of use.

The evenly dashed broken lines depict portions of the cover for electronic device and form no part of the claimed design. The dash-dot-dash line shows bounds of the claim and form no part of the claimed design.

1 Claim, 7 Drawing Sheets
